ASTROLOGICAL GAME

Paul J. Angst, Los Angeles, Calif.

Application March 3, 1939, Serial No. 259,545

3 Claims. (Cl. 273—142)

This invention relates to improvements in game devices.

The general object of the invention is to provide a game device which is instructive as well as entertaining.

Another object of the invention is to provide a game device including a base having a rotatable disk thereon with the base having pictures of activities and scenes of every day life thereon depicting the meaning and attributes of the twelve houses of astrology and the disk having thereon pictures and data thereon representing the meaning, nature, dates, symbols and ruling planets of the twelve signs of the zodiac of astrology.

A further object of the invention is to provide a game device including a base and rotatable disk both having data thereon as described together with nine spheres marked with the name or symbols of the nine planets used in the practice of astrology which are adapted to be positioned in a groove in the base and expelled therefrom by rotation of the disk.

Other objects and the advantages of this invention will be apparent from the following description taken in connection with the accompanying drawings, wherein:

Fig. 1 is a top plan view of my improved game device with the illustrations omitted;

Fig. 2 is an enlarged section taken on line 2—2, Fig. 1;

Fig. 3 is an enlarged fragmentary view similar to Fig. 1 showing the illustrations;

Fig. 4 is a top plan view of the game device showing a pad applied thereto to change the nature of the game;

Fig. 5 is a section taken on line 5—5, Fig. 4; and

Fig. 6 is an enlarged section taken on line 6—6, Fig. 4.

Referring to the drawings by reference characters I have indicated my improved game device generally at 10. As shown the device comprises a base member 12 and a rotatable member 13.

The base member 12 comprises a square bottom plate 14 having side rails 15 thereon at the edges and having a centrally located aperture 16 therein.

The rotatable member 13 comprises a disk member 17 having a central aperture 18 therein and a knob member 19.

The knob member 19 at the lower end includes a reduced hub portion 20 which is positioned in the disk aperture 18 and extends therebelow

a predetermined distance and engages the upper face of the bottom plate 14. Below the hub 20 the knob 19 includes a reduced stem 21 which is positioned in the base aperture 16. The knob 19 and the disk 17 are suitably secured together as by glueing. Thus by spinning the knob 19 the disk 17 rotates about the axis of the knob 19.

Adjacent the periphery of the disk 17 the bottom plate 14 has a circular recess 22 in the top face thereof in which a plurality of spherical members or balls 23 are adapted to be positioned. The groove 22 is so arranged relative to the periphery of the disk 17 that the balls 23 when placed in the groove engage and lean against the periphery of the disk. Thus when the disk 17 is rotated the balls 23 move slowly in the same direction as the disk and at the same time each ball revolves about its own axis in a direction the reverse of the direction of rotation of the disk. As the speed of the disk 17 increases the balls 23 are expelled from the groove 22 onto the upper face of the plate 14 the side rails 15 preventing them from leaving the base member.

The upper face of the plate 14 is divided into twelve equal spaces as indicated at 24 by suitable indicia 25 radiating from the axis of the aperture 16 to represent the twelve houses of astrology and adjacent the groove 22 each division is suitably numbered to indicate the correct house. Each of the houses 24 is divided into three equal divisions 26 by suitable indicia 27 radiating from the axis of the pin 16 and the division 24 having pictorial representations of the meaning and attributes of that particular house as clearly shown in Fig. 3.

The upper surface of the disk 17 is divided into twelve equal spaces 28 by suitable indicia 29 radiating from the axis thereof to represent the twelve signs of the zodiac of astrology. Adjacent the periphery of the disk each space 28 has suitable indicia 30 thereon to indicate the dates, symbols and ruling planet of that particular zodiac sign and inwardly of the data 29 thereon is a pictorial representation of the meaning and nature of that particular zodiac sign.

The nine balls 23 have suitable indicia 31 thereon indicating the name or symbols of the nine planets used in the practice of astrology.

In operation a player places the balls 23 in the groove 22 and spins the disk 17 whereupon the balls are expelled from the groove as previously described and stop in various ones of the houses 24. After the balls have come to rest the player determines the result by applying the laws of

astrology governing the relationship of the planets to the houses.

In Figs. 4, 5 and 6 I have indicated a mat member generally at 32 for use with the device 10 to change the nature of the game. As shown the mat 32 is made of rubber and includes a thin base portion 33 divided into thirty-six equal divisions 34 by a plurality of upwardly protruding ribs 35. The alternate areas covering thirty degrees are preferably of different colors and each area of thirty degrees is numbered to indicate the value of the space.

With the pad 32 the nine spheres 23 are used in the same manner as previously described and 15 are expelled into the spaces 34. A suitable set of rules is furnished to instruct the players in the scoring value of the various spheres 23 in relation to the various spaces 34.

From the foregoing it will be apparent that I 20 have provided a novel game device which is instructive as well as entertaining and one which is simple in construction.

Having thus described my invention I claim:

1. In a game device, a base member having an 25 upwardly extending edge flange and having a flat upper plane surface, a spinner rotatably mounted on said base, means to rotate said spinner, said base having a circular continuous upwardly opening groove in the top surface thereof adjacent the periphery of said spinner and adapted to receive a plurality of spherical members, said periphery having an uninterrupted circular outer edge overlying the inner portion of the groove, the center line of said groove being spaced from the periphery of said spinner to cause a spherical member in the groove to engage against the pe-

riphery of said spinner and to also engage the outer edge of said groove.

2. In a game device, a base member, said base member having an upwardly extending edge flange, said base member having a flat upper surface, a spinner having a flat upper face rotatably mounted on said base, said base having a circular continuous upwardly opening groove in the top surface thereof and located adjacent the periphery of said spinner, spherical members being 10 adapted to be positioned in said groove, said periphery having an uninterrupted circular outer edge overlying the inner portion of the groove, the center line of said groove being spaced from the periphery of said spinner to cause a spherical 15 member in the groove to engage against the periphery of said spinner and to also engage the outer edge of said groove, a plurality of radially extending ribs on the base and extending outwardly from the edge of said spinner. 20

3. In a game device, a base member, a spinner rotatably mounted on said base, said base having a circular continuous upwardly opening groove in the top surface thereof adjacent the periphery of said spinner and adapted to receive a plurality of spherical members, said spinner having an uninterrupted circular outer edge overlying the inner portion of the groove, the center line of said groove being spaced from the periphery of said spinner to cause a spherical member in 30 the groove to engage against the periphery of said spinner and to also engage the outer edge of said groove, a mat mounted in said base, said mat having radial ribs thereon, said mat having a central aperture receiving said spinner. 35
